UNITED STATES PATENT OFFICE.

JOHN BORYK, OF ANSONIA, CONNECTICUT.

COMBINATION-LOCK.

1,326,175.

Specification of Letters Patent. Patented Dec. 30, 1919.

Application filed June 8, 1918. Serial No. 238,860.

To all whom it may concern:

Be it known that I, JOHN BORYK, a subject of the Emperor of Austria, residing at Ansonia, county of New Haven, and State of Connecticut, have invented certain new and useful Improvements in Combination-Locks, of which the following is a specification.

This invention relates to improvements in locks adapted to be manually actuated without the use of a key.

The principal object of the invention is to provide a lock adapted to be used in connection with swinging doors and the like, the lock having a plurality of bolt elements which are moved into operative position by a combined action applied to a knob and handle respectively, means being provided whereby when the bolts are entered into their keepers to prevent their return until further manipulation of the lock operating parts.

These and other like objects are attained by the novel construction and combination of parts hereinafter described and shown in the accompanying drawings, forming a material part of this disclosure, and in which:

Figure 1 is a top plan view, showing a lock made in accordance with the invention, the cover or top plate being removed.

Fig. 2 is a transverse sectional view taken on line 2—2 of Fig. 1.

Fig. 3 is a transverse sectional view taken on line 3—3 of Fig. 1.

Fig. 4 is a longitudinal sectional view taken on line 4—4 of Fig. 1.

Fig. 5 is a fragmentary plan view, showing the parts in another position from that of Fig. 1, and

Fig. 6 is a fragmentary detail view, showing certain of the operative elements.

The lock body comprises a face or front plate 10 to which is engaged an inner rigid bar 11, and a rectangular casing having side walls 12 and rear wall 14, with which are also connected top and bottom plates respectively 15 and 16.

Reinforcing strips 18 are secured transversely of the side and back, the strips having inturned elements through which pass bolts 20, provided with nuts 21, other bolts 22 having nuts 23 connecting the face plate 10 with the bar 11.

A bar 25, parallel with the outer plate 10, is movable laterally within the casing and has secured at its ends and midway of its

length, a plurality of lock bolts 26, the bolts extending through the bar 11 and face plate 10 so as to engage with the keepers (not shown). This bar 25 is normally held 60 pressed inwardly, due to the contact of pins 28, fixed in the free ends of levers 29, the levers being pivoted upon screws 30, set in the lower casing plate 16 and moved outwardly, due to the bent flat springs 31, which 65 encircles the pivoted ends of the levers and are provided with inturned ends 32, engageable within corresponding recesses formed in the edge of the levers, the outer ends of the springs making contact against fixed 70 pins 33 also set in the casing plate 16.

Another bolt 36 is arranged centrally between the inner pair of bolts 26, and is formed with a shoulder or abutment 37, against which contacts a lever 38, pivoted on 75 a stud 39, set within the casing and held in position by a nut 40, threaded to the upper end of the stud.

The outer end of the lever 38 is secured by a pin 41 to the eye 42 of a rod 43 extending 80 through the rear wall 14 of the lock casing in such manner that when it is pressed in, the bolt 36 is forced outwardly into engagement with its keeper.

Blocks 47 are secured to the wall 16 of 85 the casing, the bar 25 moving on them and is held in position by caps 48. An arduately curved guard block 50 is also fastened upon the inner side of the plate 16, the same having a raised body 52, and journaled in the plate 16 at the axial center of the block is a spindle 54, secured by the lock nut 55, below the casing 16, the outer extending end being screw-threaded and engaged with a nut 56, set in the end of a knob 90 58, resting upon the frame-work of the door or other parts containing the lock, the knob having a longitudinal recess 59 containing a sleeve 60, passing inward through the upper cover plate 15, and formed with an eccentric 62, provided with a peripheral recess 63. A pin 61 passes through the shank of the knob, securing the sleeve 60 and spindle 54 together.

A narrow raised projection 65 is formed 105 on the upper surface of the center bolt 36, adapted to make contact with the surface of the eccentric 62 and also to enter the recess 63 at certain times, whereby the spindle and knob are prevented from being rotated.

Affixed upon the bottom plate 16, at one corner of the casing, is a bracket 70 having

a bolt 71, on which is pivoted a lever bar 72, the outer end of the lever bar being pivotally engaged with a link 74, by the screw 73, the link connecting by another screw 75 with an arm 77, formed with a hub 78, secured upon a spindle 79 extending outward through the upper plate 15 and provided with an actuating handle 80, the lever 72 passing through a recess formed in the rear end of the central lock bolt 36.

Mounted freely on the spindle 54 is a ratchet wheel 82, the teeth 102 being engageable by a pawl 83, pivoted by the screw 84 to the lever 72 near its outer end, the pawl 83 having a plurality of teeth 85 so as to contact at different points with teeth of the ratchet 82. This pawl is normally pressed into operative engagement by the dog 86, actuated by a bent flat spring 87, carried on a fixed plate 88, the dog pivoting on a screw 89, the ratchet being held from rotating in the opposite direction by a dog 92 pivoted upon a pin 93, set in a boss 94, formed with the guard frame 52 and held in operative position by a bent flat spring 95.

Secured to the lower side of the ratchet wheel 82 is another ratchet wheel 98, having cam shaped teeth 99, and formed in the periphery of wheel 98 is an open slot 100, the same occurring so as to be in register with a similar opening 101, formed in the periphery 102 of the ratchet wheel 82, the arrangement being such, that when the slots 100 and 101 are in alinement with the projection 65 of the center bolt 36, the latter can be retracted, together with the bolts 26, by action of the universal bar 25, which, as before described, is normally pressed toward the rear of the lock casing. Thus in releasing the bolts from their keeper it is necessary not only to turn the knob 58 so that the high point of the eccentric 62 is directed toward the rear of the casing, but also to manipulate the handle 80 so as to bring into position the recesses in the ratchet wheels to receive the projection 65 at which time the lock will be open.

In order to unlock the lock, the knob 58

is turned so as to bring the high point of the eccentric 62 toward the rear of the casing in order to bring the projection 65 of the bolt 36 in alinement with the slots 100 and 101. If now the handle 80 is turned, it will operate the lever 72 and the pawl 83 to rotate the ratchet wheels 82 and 98 for bringing the slots 100 and 101 therein in alinement with the projection 65 and will also operate the central bolt 36 and through the intermediary of the universal bar 25 will also operate the other locking bolts for releasing the same from their keepers, so that the door can be opened.

The locking of the lock is effected by turning the knob 58 in order to disengage the projection of the bolt 36 from the slots 100 and 101 whereupon the operation of the handle lever 80 will bring the slots of the ratchet wheels out of alinement.

Having thus described my invention what I claim as new and desire to secure by Letters Patent, is—

In a lock of the character described, comprising a casing, a knob and its spindle, an eccentric on said knob spindle, a universal bar movable laterally within said casing and normally pressed toward the rear of the same, levers pivoted to said bar, flat springs encircling the ends of said levers and stop pins against which said springs contact for normally pressing said bar inwardly, a plurality of lock bolts on said bar, a projection on the center bolt, a ratchet wheel on the knob spindle having an open slot, a second ratchet wheel secured to the lower side of the first named wheel, cam shaped teeth on said second wheel and an open slot formed in its periphery, and a lever adapted to be operated for bringing the slots of said ratchet wheels in position to receive the projection of said center bolt for allowing a retraction of said bolts by the universal bar, substantially as described and for the purpose set forth.

In testimony whereof I have affixed my signature.

JOHN BORYK.
